UNITED STATES PATENT OFFICE.

ISAAC C. WILLIAMS, OF AUBURN, WEST VIRGINIA.

FIRE-PLACE.

SPECIFICATION forming part of Letters Patent No. 315,367, dated April 7, 1885.

Application filed May 23, 1884. (No model.)

To all whom it may concern:

Be it known that I, ISAAC C. WILLIAMS, a citizen of the United States, residing at Auburn, in the county of Ritchie and State of West Virginia, have invented certain new and useful Improvements in Fire-Places; and I do declare the following to be a full, clear, and exact description of the invention, such as will enable others skilled in the art to which it applies to make and use the same, reference being had to the accompanying drawings, and to letters or figures of reference marked thereon, which form a part of this specification.

Figure 1 of the drawings is a front view of my device. Fig. 2 is a vertical sectional view of the same. Fig. 3 is a plan view, and Fig. 4 is a transverse sectional view.

This invention relates to that class of ranges and stoves called "parlor-cookers;" and it consists in the construction and novel arrangement of devices, as will be hereinafter more fully set forth, and pointed out in the appended claim.

In the accompanying drawings, A represents a range or fire-place of rectangular form, and built upon a floor, B, of brick or other proper material.

C is the front surface of the range, provided with the clip c, attached horizontally across it at its upper edge, and with the similar clips, c' and c'', horizontally across it, respectively, at its central part and a little above its lower edge.

c³ is a rectangular opening in the front between the upper and middle clip, and c⁴ is a similar opening between the middle and lower clip. The widths of these openings equal the distance between the clips, and their ends are equally distant from the sides of the range.

40 The lower edge of clip c and upper edge of clip c' have ways formed in them for the accommodation of the rectangular sliding doors D D, which, when meeting centrally against each other and against a proper stop in said ways, close the opening c³. The lower edge of clip c' and upper edge of clip c'' are provided with similar ways for the accommodation of similar doors, E E, to close the opening c⁴.

50 F is the hearth, secured to the lower edge of clip c in front of the opening c⁴ by pins fixed

to the clip, which enter proper holes in the bottom of said hearth, and f is a rectangular opening in the bottom, which may be closed by the similarly-shaped piece, f', their edges being rabbeted or otherwise fitted to each other.

G is the ash-pan, fitting snugly between the hearth and the floor B and running into the ash-pit g below the grate, the front of the range 60 below the hearth being cut away at g' for its entrance.

H is the grate, of suitable form, and situated in the usual or other proper position.

I I are jambs on each side of the grate, and against which its ends abut, built of brick or other suitable material, and J is the back wall of the grate, similarly built, the top of which inclines backward and upward from the level of the top of the grate to the back wall of the 70 chimney at the foot j of the same, which foot is on a level with the top of the range.

K is the chimney, rising vertically from the point j, with its rear wall built upon the wall L back of the range.

M M are flues beginning adjacent to the jambs in the ash-pit g below the grate, thence running horizontally back through the back wall, J, of the grate to the wall L, along which they ascend vertically to open into the chimney at its foot j.

N is the top plate of the range, made, preferably, of iron, and properly secured to the frame of the range. n n are the usual lids for the said top plate, fitting into proper openings 85 n' n', and having between them the usual removable piece.

O is a rectangular plate, provided around its edge with the depending flange o, the said flange having centrally under the ends of the plate O the pins o' o', which project downward and enter proper holes in the plate N, and bring the flange o into contact with said top plate, thus covering the openings n' n' when they are not being used.

o² is a central circular opening in the plate O, over which opening an urn or other ornamental piece rests when cooking is not going on.

The operation of this invention is as follows: 100 When the fire is burning, the direction of the main draft is from the grate along the inclosed

top of the back wall, J, to the point *j*, and thence up the chimney. In consequence of the flues M M entering the chimney at the point *j* a second upward draft is created through these flues, which will draw the ashes and dust from the ash-pit, into which said flues open, to wind up the chimney. It must be noticed that, when the doors D D and E E are closed, by removing the piece *f'* from the opening *f* in the bottom of the hearth a draft will be produced through said opening, the direction of the draft being first down into the ash-pan, which projects considerably within the range, and thence into the space below the grate.

Having thus described my invention, what I

claim, and desire to secure by Letters Patent, is—

The combination, with the parlor fire-place, of the top plate, N, having the lid-apertures, and provided with holes, as described, the rectangular plate O, having the depending flange, and pins *o'*, to enter the said holes of the plate N, substantially as shown and described.

In testimony whereof I affix my signature in presence of two witnesses.

ISAAC C. WILLIAMS.
